N. J., a corporation of New Jersey

Application July 25, 1935, Serial No. 33,184

3 Claims. (Cl. 123—169)

This invention relates to spark plugs and particularly to an improved spark plug having a novel construction facilitating the maintenance of proper temperature conditions and the avoidance of deterioration resulting from either too much or too little heat at any of the points along the path of current flow.

An object of the invention is to provide a spark plug of the type described wherein the sparking point may be kept within a suitable temperature range and excessive heat rapidly dissipated. In this connection a feature of the invention is the provision of air circulating means in two distinct regions in the plug assembly, one of which regions of air circulation operates to supplement the other and, in conjunction therewith, achieve the stated objective.

These and other objects will appear more fully in the detailed description of the invention which follows. Although only one embodiment of the present invention is illustrated in the accompanying drawing, it is to be expressly understood that this drawing is for the purpose of illustration only and is not to be construed as a limitation of the scope of the invention, reference being had for this purpose to the appended claims.

In the drawing there is shown a transverse vertical sectional view through a device embodying the invention. Referring in detail to the drawing, reference character 5 designates the body portion of the spark plug, the said body portion being provided with the usual threaded portion 6 for engagement with the engine housing to form the return circuit of the current which jumps across from the central electrode 7 to the grounded electrode 8 secured to the shell 5 in any suitable manner, as by providing the shell with an inwardly turned rim 9 on which the flange 10 of the fixed electrode 8 is adapted to be supported. The insulator 12 of suitable siliciferous material, such as porcelain, is adapted to be retained within the shell by the provision of the usual clamping nut 13 which holds the insulator against the shoulder portion 14 of the shell, a seal against escape or entry of fluid being effected at these two points by the provision of the usual gaskets 15 and 16 engaging the parts 14 and 13 respectively and also engaging the oppositely facing shoulders 18 and 19 of the insulator 12. Between these shoulders 18 and 19 the insulator is peripherally grooved, as indicated at 21, and is also internally threaded as indicated at 22, the grooves 21 being adapted to cooperate with the radial apertures 24 in the shell 5 to establish a path for the circulation of a cooling cur-

rent of air, and the threads 22 being adapted to cooperate with corresponding threads on a metallic sleeve 28 of copper or other material having good heat conducting qualities, whereby a substantial amount of heat may be taken from the electrode 7 along this region and transferred through the insulator, to be dissipated along the surfaces of the grooves 21, or radiated along the upper annular chamber 29 constituting a part of the second region of air circulation now to be described.

The second region of air circulation includes radial apertures 31 and an intersecting longitudinal aperture 32 in the terminal cap 33 within which the upper end of the electrode 7 is secured and to which the high tension current is delivered by the usual current conducting cable and connections (not shown). Due to the fact that the skirt 34 of the cap extends into the upper chamber 29 of the insulator for a considerable distance, there is an additional area of heat conducting surface from which the heat may be radiated, and thus the removal of heat from the electrode and terminal member is accelerated, and the heat thus removed, which is in addition to the heat removed along the region contacted by the copper sleeve 28 and the lower end of the insulator 12, serves to establish a decided heat differential or temperature gradient along the length of the electrode. The result is that relatively little heat finds its way past the terminal cap 33, and in this manner the cable and connections to the said cap are maintained at a temperature below that which would be injurious. As a further heat controlling factor, a washer 36 of heat resisting material, such as asbestos, may be inserted between cap 33 and the core 12.

Annular member 11, interposed between electrode 8 and the inner shoulder of the shell, serves a double purpose. It acts as a baffle as well as a heat dissipator, transferring heat from the electrode 8 to the shell by virtue of its broad surface contact with both these parts.

In assembling the plug elements the first step is to braze or otherwise permanently weld the electrode 7 within the metallic sleeve 28, and the second step is to apply a suitable cement to the threaded surfaces 22, so that upon threading the electrode carrying sleeve into the porcelain core 12 to the desired distance, the electrode will become securely bonded to the core 12 by virtue of the cement confined between the registering surfaces of the sleeve 28 and the bore of the core 12. This cementing step, in conjunction with the

gaskets 15 and 16, renders the plug air and gas tight.

What is claimed is:

1. In a spark plug, an insulator provided with an annular chamber centrally thereof, a second annular chamber extending below said first-named chamber and separated therefrom by the interposition of said insulator, and means for facilitating circulation of separate air currents in each of said chambers.
2. In a spark plug, an insulator provided with an annular chamber centrally thereof, a second annular chamber extending below said first-named chamber and separated therefrom by the interposition of said insulator, and means for facilitating circulation of separate air currents

in each of said chambers, said means including an apertured terminal member extending into said first named chamber and an apertured shell surrounding said insulator and supporting both said insulator and said terminal member.

3. In a spark plug, an insulator provided with an annular chamber centrally thereof, an electrode extending through said chamber, a terminal member engaging one end of said electrode and defining the upper limit of said chamber, and means defining the lower limit of said chamber, said means including an insulator supporting said terminal member, and a metallic sleeve adjustably engaging said insulator.

EDWARD B. NOWOSIELSKI.
